(57) **CLAIM**

The ornamental design for an automotive driving recorder, as shown and described.

DESCRIPTION

FIG. 1 is a front elevational view of an automotive driving recorder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a bottom, rear and left side perspective view thereof; and,

FIG. 10 is a top, rear and right side perspective view thereof.
